US0D1002150S

(12) United States Design Patent (10) Patent No.: US D1,002,150 S
(45) Date of Patent: * Oct. 24, 2023

(54) MASK

(71) Applicant: Guangzhou Mokaqi Network Technology Co., Ltd., Guangdong (CN)

(72) Inventor: Wanwen Zhong, Guangdong (CN)

(73) Assignee: Guangzhou Mokaqi Network Technology Co., Ltd., Guangzhou (CN)

() Term: 15 Years

(21) Appl. No.: 29/799,015

(22) Filed: Jul. 12, 2021

(30) Foreign Application Priority Data

Apr. 19, 2021 (CN) 202130222935.5

(51) LOC (14) Cl. 02-02

(52) U.S. Cl.
USPC D2/741

(58) Field of Classification Search
USPC D2/869, 741, 872; D29/108, 102, 110;
D21/660

CPC A41D 13/11
